DESIGN FOR A VELOCIPED

Clarence E. Garton, Sheboygan, Wis.

Application April 25, 1938, Serial No. 76,745

Term of patent 3½ years

To all whom it may concern:

Be it known that I, Clarence E. Garton, a citizen of the United States, residing at Sheboygan, in the county of Sheboygan and State of Wisconsin, have invented a new, original, and ornamental Design for Velocipedes, of which the following is a specification, reference being had to the accompanying drawing, forming part thereof.

Figure 1 is a side elevation of a velocipede embodying my new design and Figure 2, a rear view thereof.

I claim:

The ornamental design for a velocipede, as shown.

CLARENCE E. GARTON.
